R. CONDON.

BRUSH.

APPLICATION FILED JAN. 11, 1921.

1,413,900.

Patented Apr. 25, 1922.

UNITED STATES PATENT OFFICE.

ROBERT CONDON, OF BROOKLYN, NEW YORK.

BRUSH.

1,413,900.

Specification of Letters Patent. Patented Apr. 25, 1922.

Application filed January 11, 1921. Serial No. 436,499.

To all whom it may concern:

Be it known that I, ROBERT CONDON, a citizen of the United States, and resident of 5 216 Highland Place, Brooklyn, in the county of Kings and State of New York, have invented certain new and useful Improvements in Brushes, of which the following is a specification.

This invention relates generally to improvements in brushes and particularly to liquid feeding brushes.

The primary object of this invention is to provide a simple, effective and efficient liquid feeding brush especially adapted for 15 the printers' and lithographers' trade and allied trades, to be used for the purpose of cleaning forms, cuts, type and the like.

Another object of this invention is to provide in such a device a suitable liquid container and a bristle carrying member or holder having bristles secured therein, the said bristle holder being provided with a plurality of orifices or perforations, a central distributing cavity, and channels connecting the orifices with the central distributing cavity.

A further object of this invention is to provide in such a device valve and valve operating means secured within the container 30 or receptacle whereby the liquid to be contained in the receptacle may be allowed to pass from the receptacle through the orifices to the bristles.

A still further object of this invention is 35 to provide in such a device side-members or plates resiliently and releasably secured to the brush adapted to be adjusted horizontally and vertically, and means for keeping these side-members in a desired position.

40 A still further object of this invention is to provide a liquid feeding brush in which the bristles under the orifices may be kept in flexed position thereby assuring the said bristles being saturated by the liquid leaving the orifices.

The above and further objects in view will be more fully understood from the following description together with the accompanying drawings forming part of this 50 specification, the said description and drawings being a preferred embodiment of this invention.

In the drawings:

Fig. 1 illustrates a longitudinal section of 55 this invention.

Fig. 2 is a perspective view of the bottom

of a liquid container forming a part of this invention.

Fig. 3 is a perspective view of the bristle carrying member or holder forming a part 60 of this invention.

Fig. 4 illustrates a longitudinal section of a valve and a valve operating means (in working position) forming a part of this invention.

Fig. 5 illustrates a portion of a side-plate or member with securing means used in this invention.

In the drawings there is disclosed a liquid feeding brush consisting generally of a 70 liquid container or receptacle 11, a bristle carrying member 12 provided with bristles 13, a valve 14 and a valve operating means 15, and adjustable side-members 16.

The container 11 has a curved top 17 terminating in flat sides 18 although any other suitable shape may be used. The top 17 is provided at one end with an inlet 19, the outer end of which is engaged by a suitable cap 20, and at its other end with an orifice 80 or perforation 21 within which is secured the packing 22.

The bottom 23 of container 11 is attached, liquid tight, thereto by any suitable means and in such manner that the flat sides 18 extend somewhat below bottom 23 thereby leaving sufficient surface on each side to which bristle carrying member 12 may be attached. The said bottom is provided at the end near perforation 21 with a raised 90 portion 24 (see Fig. 2), the latter being provided with a central aperture 25. Raised portion 24 extends upwardly surrounding aperture 25, as shown at 26, thereby providing a valve seat 27 for valve 14.

The valve 14 is mushroom-shaped, the lower part 28 of which is adapted to slidably engage the wall surrounding central aperture 25, the upper part or head 29 being in closed contact with valve seat 27 when valve 100 14 is in closed position.

Attached to lower part 28 of valve 14, by means of pin 30, is one end of tension spring 31, the other end of the latter being attached by suitable means not shown, to bottom 23 105 of container 11. By means of this spring valve 14 is resiliently secured within aperture 25 and kept normally in closed position.

The valve operating means comprises a lever arrangement 32 (see Figs. 1 and 2) 110 fulcrumed at 33 on lug 34, the latter being secured to container 11. The lower end of

this lever arrangement is secured to valve 14, while the upper end protrudes outwardly from packing 22 in orifice 21 and has secured to it a suitable nob 35. By pressing down 5 upon this nob, valve 14 is made to open, against the tension of spring 31.

The bristle carrying member 12 is provided at its end adjacent raised portion 24 of bottom 23 with a plurality of orifices or 10 perforations 36, a central distributing cavity 37 disposed directly under valve 14 and a plurality of channels or grooves 38 connecting the orifices with the central distributing cavity. Fig. 3 shows a particular arrangement of the grooves and channels, some of 15 the channels connecting some of the grooves together, while others connect directly with the central distributing cavity. However, be it understood that the inventor does not 20 desire to be limited to that particular arrangement disclosed in the drawings; any other arrangement adapted to serve the purpose being contemplated.

The side-plates or members 16 are disposed at opposite ends of the brush and are 25 independent of each other. These side-plates or members are shaped preferably as shown in Figures 1 and 5 of the drawings and have formed in their upper ends 39 vertical slots 30 40, preferably two in each member, said side-plates being provided with extensions 40' projecting partially along the longitudinal sides. Secured to sides 18 of container 11 are the threaded pins 41. The side-members 35 16 releasably engage pins 41 through slots 40, the said side-members being resiliently secured on the pins by means of springs 42 disposed between sides 18 of container 11 and the side-members and the nuts 43. Vertical adjustment is made effective by slots 40 of the side-members and horizontal adjustment by operating nuts 43.

Operation:

The liquid, for instance benzine, is poured 45 into container 11 through inlet 19. When it is desired to use the brush, nob 35 is pressed down thereby opening valve 14. The liquid flows through the valve into cavity 37 from whence it distributes itself 50 through the various channels 38 and enters orifices 36 thereby moistening bristles 13 at the front of the brush.

By turning nuts 43 side-members 16 are caused to bear, more or less, upon the bristles, thereby preventing the latter from spreading. It is preferable to permanently

adjust the side-member furthest from valve 14. Then by adjusting the side-member nearest to the valve, the bristles under orifices 36 are flexed—the flexing action diminishing in intensity from the end of the brush—thereby assuring the said bristles being saturated by the liquid leaving the orifices.

When the bristles under the orifices are 60 flexed and thereby crowded or congested by the means just mentioned, the flow of the liquid after leaving the orifices is retarded, the magnitude of said retardation being dependent upon the lateral pressure of the side- 70 plate nearest the orifices, upon the bristles.

The front portion of the brush, namely, where the valve is located, is used to moisten the object and loosen the dirt therefrom, while the remainder of the brush is used to 75 finally clean it. If the bristles become worn the slots in the side-members permit of the latter being raised sufficiently, so as to make the bristles effective again.

My device may be used in the printing, 80 lithography, and allied arts, in the tailoring, cleaning and allied trades and also for domestic purposes.

Be it understood that the inventor shall not be limited to the particular construction 85 described above and therefore reserves for himself the right to make alterations, amendments and changes consistent with his idea.

Having thus described the invention, what is claimed is:

1. The combination with a liquid feeding brush provided with a container, of side members arranged to engage the bristles, said side members being yieldingly secured to the brush and adapted to be adjusted 90 vertically and horizontally.

2. The combination with a liquid feeding brush including a container, a brush member and means for regulating the flow of a liquid from the container to the brush member when desired, of side-members disposed to engage the bristles, said side-members being resiliently secured to the brush and adapted to be adjusted vertically and horizontally.

Signed at New York, in the county of New York and State of New York, this 4th day of January, A. D. 1921.

ROBERT CONDON.

Witness:

H. L. VAN SYCKEL, Jr.
